UNITED STATES PATENT OFFICE.

LOUIS P. THORNTON, OF PORTLAND, OREGON.

INDOOR FOOTBALL GAME.

Application filed December 23, 1925. Serial No. 77,210.

The object of my invention is to provide a game that may be played by placing the device upon an elevated support and have players disposed around the outer edge of the same and manipulating rods disposed within the wall structure surrounding the field and which form guides for cross rods having, depending therefrom, small figures adapted to strike the foot ball and move the same in a highly animated manner about the field. The depending figures being so arranged that the path of the ball may be entirely closed to the passage of the ball across the field, depending upon the skill and agility of the players.

A further object of my invention is to provide a carrying case, the same to be formed of the bottom side and end walls of the device and when the same are closed to form a carrying case for the rods, ball, goals and other paraphernalia incident and belonging to the device.

Still further objects of my invention consists in attaching the figures to the rods in such a manner that a certain flexibility and accumulated tension may obtain in the figures when the ball is stuck, thus imparting to the ball an intensity of movement by the players.

Still further objects of my invention consist in providing a game wherein, and whereby, the players may assemble about the game board, placed upon a table or other suitable support, and get all of the thrills from the playing of the game that may be secured by the onlooker at the regular game of foot ball with the additional advantage of the actual participation in the game, by the players indulging in the game.

Still further objects of my invention consist in the production of a portable game of foot ball wherein the field of play is constructed proportionally and upon a reduced scale, and wherein the field of play is divided into the standard markings, the device being constructed of a minimum number of parts and one that will not easily get out of order and that may be easily made.

With these and incidental objects in view, the invention consists in certain novel features of construction and combination of parts, the essential elements of which are set

forth in the appended claims, and a preferred form of embodiment of which is hereinafter shown with reference to the drawings which accompany and form a part of this specification.

I attain these objects by the mechanism illustrated in the accompanying drawings, in which:—

Fig. 1 is a top plan view of the assembled mechanism in position for play.

Fig. 2 is an end view of the mechanism shown in Fig. 1.

Fig. 3 is an end view of the mechanism shown in Fig. 2 when the same has been hinged about the central hinged connection to afford portability to the same.

Fig. 4 is a top view of the mechanism shown in Fig. 3.

Fig. 5 is a side view of the mechanism shown in Figs. 3 and 4, with carrying straps placed therearound to facilitate the transporting of the same.

Fig. 6 is a side view of the end closure illustrated detached from the case when folded for portability.

Fig. 7 is an end view of the mechanism shown in Fig. 6.

Fig. 8 is a fragmentary side view of the mechanism shown in Fig. 1.

Fig. 9 is a detached view of one of the manipulative rods carrying the player depending therefrom.

Fig. 10 is an enlarged end view of the mechanism shown in Fig. 9.

Like reference characters refer to like parts throughout the several views.

The game is constructed primarily of the two side members which form the bottom of the structure and which also form the field of play. 1 and 2, these are hinged together by suitable hinges 3, disposed central from the side walls. To maintain the ball within suitable enclosure I provide side rims 4, disposed at either side of the field and of a sufficient height to maintain the ball within the enclosure when the game is being played. End walls 5 are provided for the same purpose of maintaining the ball within the enclosure, and upon the field of play. Openings are disposed central of either end through the end closure 5, and of the standard proportional width between the goal

posts of the standard field. The object of the game is to permit the players of the opposite side to prevent the passage of the ball through the goal, which when accomplished counts as one goal for the opposite players. A suitable projection 6, is disposed central of each end and is closed by suitable netting or screen or other material 7, adapted to maintain the ball within the goal, once the same has passed through the goal exit. Cross rods 8 are disposed transversely of the field of play and are maintained in a relatively fixed position due to the same passing through the wall 2 of the rim, the same may be made to pass through screw eyes 9, instead of through the wall structure. These rods may have a lateral movement imparted thereto, as well as a movement of rotation, but otherwise the movement of the same is within these fixed limits. Rings or other projections 10, are disposed about the cross rods and limits the lateral movement of the cross rods within certain limits as the same comes in contact with the screw eyes, or side walls of the rim. I have found best results are obtained where these bands are placed at different distances from the center rods. The rods to be placed or used in the center of the field to have less lateral movement imparted thereto than the ones next thereto; the end rods having the greatest freedom of lateral movement. I have also found most satisfactory results are obtained, wherein an even number of players are indulging in the game, and have therefore shown in the drawing eight cross rods, four of which are disposed at either side of the center of the field. Upon the central member of these rods or the one nearest the center of the field, I have placed five men and upon the next of the cross rods I have placed three men and upon the third cross rod from the center of the field, I have placed two men. The end rod carries but one man, that of the safety or the goal keeper. The men are shown at 11 and are in the form of a rigid plate, preferably of metal and have the player in the form of a printed figure attached thereupon, as shown at 11. The members of the opposing teams are preferably printed in different colors. To afford flexibility to the player I have found best results are obtained wherein the rigid plate is attached to the cross rod through the medium of a rubber band or spring 12, the same being endless and passes around the cross rod 8 and the rigid plate 11, so that as the ball is struck by the rigid plate the holding band 12, is flexed and an intensified movement is imparted to the ball. The ball is shown at 13. To prevent a dead space being formed at either corner of the field into which the ball may be forced and at which the same may come to rest and become inactive, I have placed inclined members 14

of such an inclination that should the ball be placed thereupon the same will roll back upon the field where the same may be reached by one of the participants of the game.

To afford portability to the game as a whole, I have hinged the two side sections together so that as the side sections are closed about the hinges a box like structure is formed into which the cross bars, balls, goals and other parts may be placed to permit the transportation of the game from place to place. When the side walls are hinged about the hinges, this will leave one of the walls open, and at the same time the goal openings will be in an open position also, for the closing of these openings, I have provided a closure member 15, having two end members 16 and 17, of a sufficient length and width to close the goals. Fastenings as hooks 18 and 19, may be used to maintain the closure in fixed position. Carrying straps 20 and 21, may be passed around the assembly and a handle member 22, secured thereto for carrying the complete and assembled unit.

While the form of mechanism herein shown and described is admirably adapted to fulfill the objects primarily stated, it is to be understood that it is not intended to confine the invention to the one form of embodiment herein shown and described, as it is susceptible of embodiment in various forms all coming within the scope of the claims which follow:

What I claim is:—

1. A new and improved football game embodying a pair of field members each provided with one side and two end walls, hingeably secured together at the upper inner edges of each end wall; said field members when extended representing a miniature football field; parallel rods loosely mounted above said field; not less than one effigial element yieldably suspended from each of said rods; a cut-away portion formed in each of the end walls, to form a rectangular opening therethrough when the first mentioned field members are extended; an exterior screened closure removableably embracing each of said rectangular openings; and a member diagonally disposed between the outer edges of each rectangular opening and the adjacent side wall.

2. A new and improved football game embodying a pair of field members each provided with one side and two end walls, hingeably secured together at the upper inner edges of each end wall; said field members when extended representing a miniature football field; parallel rods loosely mounted above said field; means provided to limit the longitudinal movement of said rods; not less than one effigial element yieldably suspended from each of said rods; a cut-away

portion formed in each of the end walls, to opening and the adjacent side wall; and a form a rectangular opening therethrough detachable closure element securable to the when the first mentioned field members are open side and end portions of said device 10 extended; an exterior screened closure when the field members are folded on each 5 movably embracing each of said rectangular other. openings; a member diagonally disposed between the outer edges of each rectangular

LOUIS P. THORNTON.
